(57) **CLAIM**

The ornamental design for a part of caliper for brake disc, as shown and described.

DESCRIPTION

2. Part of caliper for brake disc

2.1 is a front elevation view of a part of caliper for brake disc embodying my new design;

2.2 is a front elevation view thereof;

2.3 is a rear elevation view thereof;

2.4 is a bottom plan view thereof;

2.5 is a top plan view thereof;

2.6 is a left side elevation view thereof; and

2.7 is a right side elevation view thereof.

The design can be made in any colour or combination of colours or shades and in any material and external treatment.

1 Claim, 7 Drawing Sheets
